United States Patent Office

Des. 179,550
Patented Jan. 15, 1957

179,550

LAVATORY

Walter D. Teague, Annandale, N. J., Robert J. Harper, Scarsdale, and Alban G. Jackson, New York, N. Y., assignors to American Radiator & Standard Sanitary Corporation, New York, N. Y., a corporation of Delaware

Application December 9, 1955, Serial No. 39,265

Term of patent 14 years

(Cl. D4—2)

Fig. 1 is a view in perspective of a lavatory showing our new design,

Fig. 2 is a top plan view of the lavatory,

Fig. 3 is a view in side elevation of the lavatory, and

Fig. 4 is a view in front elevation of the lavatory.

We claim:

The ornamental design for a lavatory, substantially as shown.
